UNITED STATES PATENT OFFICE.

ALBERT P. HOLMAN, OF PORTSMOUTH, NEW HAMPSHIRE, ASSIGNOR TO
ROCKINGHAM SHOE COMPANY, OF SAME PLACE.

SHOE.

SPECIFICATION forming part of Letters Patent No. 234,187, dated November 9, 1880.

Application filed September 25, 1880. (No model.)

To all whom it may concern:

Be it known that I, ALBERT P. HOLMAN, of Portsmouth, of the county of Rockingham and State of New Hampshire, have invented 5 a new and useful Improvement in Shoes; and I do hereby declare the same to be described in the following specification and represented in the accompanying drawings, of which—

Figure 1 is a top view, Fig. 2 a side elevation, and Fig. 3 a rear view, of a shoe containing 10 my invention. Fig. 4 is a top view or pattern of the vamp, quarters, and strengthening-tongues, showing how they are formed in one piece of leather or material. Fig. 5 is a view 15 of one of the side pieces. Fig. 6 is a horizontal section taken through the ankle part of the shoe, and showing the arrangement of the lining, the side pieces, and the strengthening-tongues.

One important characteristic of my improved 20 shoe is that the vamp *a*, quarters *b b*, and the strengthening-tongues *c c* are in one piece of material and formed thereof in manner as shown in Fig. 4, the strengthening-tongues being 25 subsequently raised above or turned up from the quarters and lapped on the side pieces, *d d*, which extend between the said tongues and the lining *e*. Each tongue is seamed to its side piece and the lining thereof by stitching 30 at the edges of the tongue, as shown at *f f*. The side pieces project above the quarters, and like them are seamed together, the seam of the side pieces being shown at *g* in Fig. 3, and that of the quarters at *h* in the said figure. Each of the quarters laps on one of the 35

side pieces, and is stitched to it in the lap and along the upper edge of the quarter, as shown at *h'*.

The lacing-hooked eyelets *i* are inserted in the strengthening-tongues and through them, 40 the lining, and the side pieces, the said tongues thus constituting stays to the side pieces and the eyelets, the latter being supported thereby to much better advantage than they are when arranged in side pieces and lining without 45 any strengthening-tongues arranged and combined therewith and the vamp and quarters, in manner as explained.

In the United States Patent entitled "Re-issue No. 7,912" a shoe is represented having 50 the instep and leg part of its upper consisting of a seamless back, having inserted within it a top quarter, the remaining part of the upper, or that below the instep, being a separate and distinct piece of material, all of which differs 55 from an upper constructed in accordance with my invention, such upper being composed of two pieces only and seamed at the back of the heel. Therefore

I claim—

The upper composed of the vamp, quarters, and strengthening-tongues formed in one piece of material, as set forth, in combination with the side pieces arranged and connected therewith and with the lining, all being substantially as described and represented.

ALBERT P. HOLMAN.
